(57) CLAIM

The ornamental design for a combined warning light and siren housing for emergency vehicles, as shown and described.

DESCRIPTION

FIG. 1 is a front elevational view of the combined warning light and siren housing for emergency vehicles showing our new design;

FIG. 2 is a rear elevational view thereof;

FIG. 3 is a right side elevational view thereof; the left side elevational view being a mirror image of the right side elevational view;

FIG. 4 is a top plan view thereof; and,

FIG. 5 is a bottom plan view thereof.
